ATTORNEY.

UNITED STATES PATENT OFFICE.

JOSEPH MENGE, OF POINT MICHEL, LOUISIANA.

DREDGING-BUCKET.

SPECIFICATION forming part of Letters Patent No. 274,358, dated March 20, 1883.

Application filed May 2, 1877. Renewed August 30, 1879.

To all whom it may concern:

Be it known that I, JOSEPH MENGE, a resident of Point Michel, parish of Plaquemine, and State of Louisiana, have invented a certain new and useful Improvement in Dredging-Buckets; and I do hereby declare the following to be a full, clear, and correct description of the same, reference being had to the annexed drawings, making a part of this specification.

My invention relates to the production of a dredge-bucket which can effectively operate in any description of soil, and which will discharge the whole of its contents at the requisite moment with unerring certainty.

The nature of my invention will be readily understood by referring to the accompanying drawings, whereon—

Figures 1 and 2 represent side elevations of my improved bucket. Fig. 3 is a plan or top view thereof, and Fig. 4 shows the application of a number of my buckets to the ordinary machinery of dredge-boats.

This device may be made of iron or of any other suitable material; and it consists of a dredging-bucket composed of two sections, A and B, which are connected together on each side by means of links C D, in a manner that will admit of the distance between the two being automatically increased or decreased during the operation of the machine. To the rear end of the lower section, B, is hinged a bottom or

end piece, E, which is prevented from opening outward by reason of flanges or stops formed in either the upper or lower section, as found most convenient.

F F are stops on the sides of the lower section for limiting the forward movement of the links and upper section, as shown in Fig. 2. The mouth of the bucket should be made somewhat wider than the rear end, as shown at Fig. 3, in order that the links may be protected from any undue pressure of earth.

If desired, the links can be provided with a series of holes, as shown in dotted lines at Fig. 1, in order that the two sections may be adjustably connected.

Having described my invention, what I claim as new, and desire to secure by Letters Patent, is—

1. In combination with an endless carrier, a dredging-bucket constructed of two sections hinged together by means of pivoted arms, substantially as described.

2. The dredge-bucket herein described, composed of sections A and B, hinged bottom E, links C D, and stops F F, for the purpose set forth.

In testimony whereof I have hereunto affixed my hand.

JOSEPH MENGE.

In presence of—
F. H. ZAERINGER,
A. MERCADAL.
